UNITED STATES PATENT OFFICE.

MATTHEW MOLONEY, OF CHRISTCHURCH, NEW ZEALAND.

FIRE-ALARM.

1,109,859.

Specification of Letters Patent.

Patented Sept. 8, 1914.

Application filed February 14, 1912. Serial No. 677,593.

To all whom it may concern:

Be it known that I, MATTHEW MOLONEY, a citizen of the Dominion of New Zealand, and residing at Christchurch, in the Provincial District of Canterbury, in the Dominion of New Zealand, have invented certain new and useful Improvements in Improved Fire-Alarms, of which the following is a specification.

10 This invention relates to that class of fire alarms which operate by closing an electrical circuit by the expansion of metal under heat.

According hereto, the heating of a sleeve 15 causes the withdrawal of a rod against which the short arm of a lever rests, the long arm thus closing an electric alarm circuit and giving warning of an outbreak of fire. The mechanism employed comprises a 20 casing in which is pivoted a bell crank lever having a short and a long arm. The short arm bears against a rod slidable in a sleeve projecting from the casing. The rod is furnished with a nut upon its end whereby the 25 lever may be adjusted with accuracy. The long arm of the lever is provided with a platinum bridge adapted to close upon contact points insulated from the casing and connected to an alarm circuit on one, and to 30 an electric battery on the other side. Heat causes the sleeve to extend and withdraw the rod, thus allowing the short arm of the lever to recede and the bridge on the long arm to touch the contact points, whereupon 35 the electric circuit is closed and a bell or other alarm sounded. The lever is made to fall by gravity, or in other positions is made to close the circuit by a spring.

The invention is illustrated in the accompanying drawing wherein:—

Figure 1, is a plan, Fig. 2, a side elevation, Fig. 3, a section on A—A, Fig. 1.

The bell crank lever having the long arm 1 and short arm 2 is pivoted at 3 and carries 45 the bridge piece 4 at its outer end, which when the lever falls is adapted to establish electrical communication between the respective contact points 5 and 6, which are respectively in communication with the terminals 7 and 8 from the electrical bell circuit. The casing 9 has a projecting extension or sleeve 10, in which is arranged a rod 11 having an adjusting nut 12 screwed upon it at one end, the nut 12 having a screwed 50 projection 15 which screws into a screw-threaded aperture in the end of the exten-

sion 10. The rod 11 bears at its other end against the short arm 2 of the lever, thereby normally maintaining it in such position that the bridge piece is clear of the contact 60 points 5 and 6. The slot 13 in the end of the rod 11 permits it to be held if necessary while the locking nut is being turned to adjust the length of the rod to regulate the distance between the bridge piece and the 65 contact points. The normal position of the lever is shown in full lines in Fig. 2, the rod 11 bearing against the short arm 2 and holding the lever with the bridge piece 4 just clear of the contact points 5 and 6. 70 The dotted lines show how the lever may be turned upon its pivot, after removing the cover 14 of the casing, to give access to the contact points. It will be seen that upon extension of the sleeve 10 under the action 75 of heat, the rod 11 is moved outwardly and releases the lever, which falls by gravity and closes the electric circuit of the alarm bell, which may be located in any convenient position. 80

What I do claim and desire to secure by Letters Patent of the United States is:—

1. An improved alarm comprising a casing, having a removable cover, a pair of contacts located within said casing, said contacts being included in an electric circuit, a lever pivoted in said casing, an expandable sleeve secured to the outside of said casing, and a rod secured to the other end of said sleeve and projecting through said 90 casing into engagement with the lever located therein, said rod, when the sleeve expands, being moved out of engagement with said lever to allow same to bridge said contacts and close said circuit. 95

2. An improved alarm comprising a casing having a removable cover, a pair of contacts located within said casing, said contacts being included in an electric circuit, a lever pivoted in said casing, an expandable 100 sleeve secured to the outside of said casing, and a rod secured to the other end of said sleeve and projecting therethrough into engagement with the lever located in said casing, said rod, when the sleeve expands, being moved out of engagement with said lever to allow same to bridge said contacts and close said circuit. 105

3. An improved alarm comprising a casing having a removable cover, a pair of 110 contacts located within said casing, said contacts being included in an electric cir-

cuit, a lever pivoted in said casing, an expandible sleeve secured to the outside of said casing, a rod secured to the other end of said sleeve and projecting through said 5 casing into engagement with the lever located therein, said rod when the sleeve expands, being moved out of engagement with said lever to allow same to bridge said contacts and close said circuit, screw threads 10 formed on said rod, and a nut carried by

said sleeve and engaging said screw threads for adjusting the rod relatively to the sleeve.

In testimony whereof I have signed my name to this specification in the presence of two witnesses.

MATTHEW MOLONEY.
